UNITED STATES PATENT OFFICE.

T. C. HARGRAVES, OF SCHENECTADY, NEW YORK.

IMPROVEMENT IN THE CUTTING APPARATUS OF HARVESTERS.

Specification forming part of Letters Patent No. 33,941, dated December 17, 1861.

To all whom it may concern:

Be it known that I, T. C. HARGRAVES, of Schenectady, in the county of Schenectady and State of New York, have invented a new and Improved Sickle or Cutting Device for Grain and Grass Harvesters; and I do hereby declare that the following is a full, clear, and exact description of the same, reference being had to the annexed drawings, making a part of this specification, in which—

Figure 1 is a plan or top view of my invention. Fig. 2 is a transverse vertical section of the same, taken in the line $x x$, Fig. 1.

Similar letters of reference indicate corresponding parts in the several figures.

The object of this invention is to obtain a simple and efficient cutting device for grain and grass harvesters, one that cannot choke or clog, and one that will be extremely durable and operate with less power than those of usual construction.

The invention consists in the employment or use of two reciprocating toothed blades placed one over the other and operated simultaneously in opposite directions by reverse cranks, in connection with guard-fingers, set-screws, and a finger-bar, all arranged substantially as hereinafter shown and described.

To enable those skilled in the art to fully understand and construct my invention, I will proceed to describe it.

$A A'$ represent two reciprocating sickles, which are constructed in the usual way, to wit: V-shaped cutters or teeth a being formed at one side of steel plates b , the length of the teeth being equal to the width of the plates, as clearly shown in Fig. 1. The sickles $A A'$ are placed one directly upon the other, the lower sickle, A' , resting on a finger-bar, B , which is secured to the front end of the platform, as usual.

C represents the fingers, which are attached to the finger-bar B . These fingers are of the usual form, and are attached to the under side of the bar B . The fingers, however, are not provided with any cap or top, a shallow recess, c ,

only being made horizontally in the front part of the fingers to receive the ends of the cutters or teeth a , as shown clearly in Fig. 2. The finger-bar B is just equal in width to the plates b of the sickles, $A A'$, and the two sickles are kept in proper contact by means of screws $f f$, passing through guides $g g$, which project over the top plate, b , of the sickle and underneath the finger-bar B , the upper screw, d , bearing on the plate b of the upper sickle, and the lower screw bearing against the under side of the plate b of the lower sickle. (See Fig. 2.)

On the upper surface of the plate b of the lower sickle, A' , there is secured a metal bar or strip, h . This strip is at the back part of plate b , and has a tendency to keep the cutting-edges of the cutters or teeth a in contact by screwing up the screws f . The number of fingers C are equal to the number of teeth a of the sickles, and the length of stroke of each sickle is equal to half the width of the spaces between the fingers.

$D D$ represent the cranks, and $E E$ the rods, by which the sickles are driven. By this arrangement the sickles are operated with a short stroke, and the cutting operation is rendered very effectual. The fingers C protect the cutters or teeth from stones or stumps, or any irregularities of surface, and the teeth and blades may be made quite thick—much thicker than the cutters or teeth of ordinary sickles—and still operate perfectly. The two sickles, operating as described, prevent the possibility of choking or clogging.

Having thus described my invention, what I claim as new, and desire to secure by Letters Patent, is—

The combination of the two reciprocating toothed cutters $A A'$, recessed fingers $C c$, set-screws $f f$, guard $g g$, and plate h , all constructed, arranged, and operating in the manner and for the purposes herein shown and explained.

T. C. HARGRAVES.
